Primary Examiner — Robert M. Spear

(74) Attorney, Agent, or Firm — Birch, Stewart, Kolasch & Birch, LLP

(57) **CLAIM**

The ornamental design for a digital sign, as shown and described.

DESCRIPTION

1. Digital Sign

1.1 : Perspective

1.2 : Front

1.3 : Back

1.4 : Left

1.5 : Right

1.6 : Top

1.7 : Bottom

1 Claim, 7 Drawing Sheets(56)
